United States Patent Office

Des. 210,683

Patented Apr. 2, 1968

210,683

NIGHT LIGHT

Richard K. Tyler, 14858 Round Valley Drive,
Sherman Oaks, Calif. 91403

Filed May 3, 1967, Ser. No. 6,936

Term of patent 14 years

(Cl. D48—20)

FIG.1.

FIG.2.

FIG.3.

FIG.4.

FIG.5.

FIGURE 1 is a perspective view of a night light showing my new design;

FIGURE 2 is a top plan view thereof;

FIGURE 3 is a side elevational view thereof;

FIGURE 4 is a front elevational view thereof; and,

FIGURE 5 is a rear elevational view thereof.

I claim:

The ornamental design for a night light, substantially as shown and described.
